(57) **CLAIM**

The ornamental design for a diaper bag, as shown and described.

DESCRIPTION

FIG. 1 is a front perspective view of a diaper bag showing our new design;

FIG. 2 is a front perspective view of a diaper bag showing an in-use status;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the figures depict stitching and form no part of the claim.

The broken lines showing zipper tread depict claimed portions of the diaper bag.
